UNITED STATES PATENT OFFICE

1,922,288

SEAM PRESSING MACHINE

William Hamann, Irondequoit, N. Y., assignor
to United Shoe Machinery Corporation, Pat-
erson, N. J., a Corporation of New Jersey

Application July 6, 1928. Serial No. 290,806

19 Claims. (Cl. 223—28)

This invention relates to seam pressing machines and is herein illustrated as embodied in a seam pressing machine of the type disclosed in Letters Patent of the United States No. 1,833,-
5 930, granted on December 1, 1931, upon an application filed in the name of George Boulton.

It is customary, during the usual operation of seam pressing machines when operating upon certain classes of work, for the work to be
10 "backed out" instead of being fed past the entire work-engaging surface of the ironing block. The rapidity with which work of this sort may be passed through the machine depends, in a large measure, upon the facility with which the
15 operator may retract the ironing block from the work-supporting feed roll, thereby freeing the work so that it may be withdrawn in the most convenient manner. In machines of the type shown in the patent referred to, a seam ironing block is spring pressed toward a rotating work-supporting roll and may be retracted from the roll by depressing a treadle which is connected with the ironing block in such a way that the depression of the treadle, which is accompanied by a deflection of the spring, is resisted by the spring pressure upon the ironing block.

In view of the foregoing, and in accordance with a feature of the present invention, the backing out of the work in the manner before referred to is facilitated by means for retracting the ironing block without moving or effecting, and hence without energizing, the resilient means which urges the block toward the work supporting roll. To this end, in the illustrated machine means for retracting the ironing block, which means normally transmits the pressure of the resilient means to the ironing block, is constructed and arranged to relieve the pressure of the resilient means as the block is retracted; but the above is accomplished without removing the stress from the resilient means. As shown, this ironing block retracting means is interposed between the resilient means and the ironing block and comprises a toggle mechanism which is operable by a substantially constant force irrespective of the strain in said resilient means successively to relieve the pressure of the resilient means on the ironing block and to retract the ironing block from its operative position. Since, by the use of the illustrated mechanism, the ironing block may be retracted without energizing the resilient means or materially relieving the strain therein, the operator may retract the block with a prac-

tically negligible but constant amount of effort regardless of the resilient force urging it toward the feed roll.

The illustrated embodiment of the invention, including other features not heretofore specifically pointed out, will now be described, reference being had to the accompanying drawing, in which

Fig. 1 is a sectional elevation of a machine embodying the invention;

Fig. 2 is a sectional view taken along the line II—II of Fig. 1; and

Fig. 3 is a perspective view, partly broken away, of the work support.

The illustrated seam pressing machine, which may be used for pressing seams in articles made of cloth or leather, is adapted to press the seams in caps and is provided with a work-supporting feed roll 4, a stationary work support 6 arranged to cover portions of the feed roll and support the work as it is being presented to the machine, a seam-opening plow 8 having on each side thereof a seam-guiding finger 10, and a heated presser member or ironing block 12. The plow 8 is carried by a vertical rod 14 which is slid-
20 able in guideways formed in lugs 16, 18 projecting from the frame of the machine. A spring 20 surrounding the rod 14, between the lug 16 and a collar 22 fixed on the rod, urges the plow downwardly and tends to hold the plow in a position determined by an adjusting nut 24 on the upper end of the rod and arranged to engage the lug 16. The seam-guiding fingers 10 comprise thin, resilient strips the upper ends of which are fixed to the upper portion of the plow 8 by means of screws such as 26 and are adjustable sidewise by means of screws 28 the inner ends of which engage the central portion of the plow member. By adjusting the seam guiding fingers they may be made the better to accommodate varying thicknesses and kinds of work.

A presser-foot 30 is provided with a yoke-shaped member having rearwardly curved arms arranged to straddle the plow and the seam-guiding fingers and carrying at the lower end of each of its arms a freely rotatable roll 32 the periphery of which engages that of the work-supporting feed roll 4 at either side thereof. The presser-foot 30 is secured to the lower end of a vertical rod 34 mounted for yielding, sliding movement in guideways formed one in an extension of the lug 16 and the other in a lug 36. The presser-foot 30 is urged downwardly toward the work, and is adapted to be held in

yielding, feeding engagement therewith, by means of a spring 38 encircling the rod 34 between the lug 16 and a collar 40 adjustably fixed on the rod. As shown, a nut 42, threaded on the upper end of the rod 34, is adapted to engage the upper side of the lug 16 adjustably to limit the downward movement of the presser-foot toward the feed roll.

In the illustrated machine, for the purpose of lifting the plow with the guiding fingers and the presser-foot with the ironing block so as to facilitate the backing of the work out of the machine, extensions 44, 46 project rearwardly from the collar 40 and plow 8, respectively, and into the path of movement of the collar 22 and a forward portion 48 of the ironing block 12, respectively. By the above-described means, the presser-foot and the plow with the guiding fingers are retracted substantially simultaneously with a retractive movement of the ironing block, thereby providing a clear passage for withdrawing the work from beneath the ironing block.

The illustrated work support 6 has a surface which is substantially spherical in form and covers the feed roll 4 in such a manner as to eliminate the danger of oil or grease from its bearings reaching the work. The work support 6 is clamped to the frame of the machine by means of a screw 50 which passes through an elongated slot 52 in a web 54 (Fig. 3), allowing the support to be adjusted heightwise of the feed roll.

Except in certain respects hereinafter pointed out, the construction and arrangement of the parts of the present machine as thus far described are substantially the same as those of the corresponding parts in the machine shown and described in the patent hereinbefore referred to.

As embodied in the machine herein described, the ironing block 12 is secured to a carrier 56 which is slidably mounted in a guide 58 pivoted to the frame of the machine by means of trunnions 60 (Fig. 2). The reduced end of a screw 62 (Fig. 1) carried by the guide 58 engages a keyway 64 in the carrier 56, thereby to prevent rotation of the carrier relatively to the guide. The guide 58 may be held in any adjusted position by means of a screw 66 engaging the frame and passing through an arcuate slot 68 in an upstanding lug 70 integral with the guide 58. A spring 72 is coiled about and abuts the lower end of a rod 74 slidably mounted in a bushing 76 having threaded engagement with the frame as at 78 and adapted to be locked to the frame by a check nut 80. A nut 82 and check nut 84 are threaded upon the upper end of the rod 74 adjustably to limit the downward displacement of the rod 74 and hence to regulate the strain in the spring 72. Interposed between the lower end of the bushing 76 and the upper end of the spring 72 is one extremity of a lever 86 which is pivoted to the frame about a stud 88 and which imparts the stress of the spring 72 to the carrier 56 through a toggle comprising links 90, 92 pivotally connected at 94, the link 90 being pivoted at 96 to the lever 86 and the link 92 being pivoted at 98 to the carrier 56.

From the foregoing, read in connection with the drawing, it will be apparent that the lowermost position of the ironing block or its proximal position with respect to the roll 4 may be determined by the regulation of the bushing 76,

and that the resistance offered to the work by the ironing block may be regulated by altering the position of the nuts 82 and 84 on the end of the rod 74 which resists any downward force of the spring 72 imparted to it through the arm 86, the toggle 90, 92, the carrier 56 and the ironing block 12, on account of being lifted by the work as it passes thereunder.

The carrier 56 and the guide 58 are slotted, as at 100 and 102, to accommodate the toggle link 92 and an arm 104 which is connected at one end with the knuckle joint 94 of the toggle and at the other end to an arm 106, as shown at 108. The arm 106 is fixed upon a rock shaft 110 mounted in the frame of the machine. An arm 112 is fixed to the end of the rock shaft 110, at the rear of the machine, and may be operated by a treadle (not shown) through a rod 114 which connects the arm 112 with the treadle which may be depressed to retract the ironing block with a minimum of effort on the part of the operator since the strain in the spring 72 is not materially altered when the toggle is broken. A suitable guard such as 116 is provided upon each side of the ironing block to prevent accidental contact therewith.

In operation, the work, such as a cap for instance, is placed display side down over the work support 6 so that an upstanding projection 118 upon its top portion engages the vertex of the seam to be pressed. As the work passes the plow 8, the upstanding margins of the seam are directed between the inturned lower ends of the guide fingers 10. At this point the work is about to pass underneath the roll 32, thereby assisting in feeding the work to the ironing block. If the seam is of short length; or if for any other reason it is not desired to feed the work past the entire work-engaging face of the ironing block, the ironing block may be quickly and easily retracted by the operator and by a slight pressure on the treadle which is substantially constant irrespective of the strain in the spring 72, since in breaking the toggle the spring is rendered inoperative. Such a pressure on the treadle will rotate the arms 112 and 106 in clockwise direction and, through the arm 104, will draw the knuckle 94 of the toggle 90, 92 in the direction of the arm 104. As soon as the toggle links are moved out of alignment the spring 72, acting through the lever 86, will assist the operator in collapsing the toggle until the end of the lever abuts the inner end of the bushing 76. A continued treadle pressure, great enough only to overcome the weight of the block and the resilient pressure of the presser foot 30 and plow 10, will result in the complete retraction of the operating tool whereby the work may easily be removed from the machine.

While no great amount of force is necessary to retract the ironing block illustrated in the above-mentioned patent, continued and frequent operation of the treadle of the above-mentioned machine becomes wearisome to the operator before the completion of a day's work. It is obvious, in view of the foregoing description of the illustrated machine, that the block may be retracted by means of the toggle and treadle mechanism associated therewith without energizing the spring 72, and hence the amount of work required of the operator in the use of the machine is relatively slight.

Having thus described my invention, what I claim as new and desire to secure by Letters Patent of the United States is:

1. In a seam ironing machine, a work support an ironing block, a presser foot, resilient means normally urging said block toward said support, and means constructed and arranged to retract both the block and the presser foot without moving said resilient means. 5 80
2. In a seam ironing machine, a work-supporting feed roll, an ironing block, resilient means urging said block toward said roll, means whereby the pressure of the block against the work on the roll may be regulated, and means constructed and arranged to be operable by substantially a constant force, irrespective of the stress in said resilient means, to retract said block from its operative position. 10 85
3. In a seam ironing machine, a work support, an ironing block mounted for movement toward and from said support, an adjustable stop, means for urging said block toward said support, and means connecting said last-mentioned means and said block arranged to engage said stop whereby the movement of the block toward the support is limited. 15 90
4. In a seam ironing machine, a work-supporting feed roll, an ironing block, resilient means urging said block toward said roll, means for regulating the pressure of the block against the work on the roll, and means interposed between the block and said resilient means and constructed and arranged to be operable by substantially a constant force, irrespective of the stress in said resilient means, to retract said block from its operative position. 20 95
5. In a seam ironing machine, a work-supporting feed roll, an ironing block, resilient means normally urging said block toward said roll, means for adjustably limiting the proximal position of the block with respect to the roll, and means constructed and arranged to render said resilient means inoperative without removing the strain therefrom. 25 100
6. In a seam ironing machine, a work support, an ironing block mounted for movement toward and away from said support, a stop, resilient means for urging said block toward said support, a toggle for retracting said block from said support, means for operating said toggle constructed and arranged normally to hold said toggle in straightened position, and means connecting said toggle and resilient means arranged to engage said stop whereby the proximal position of said block with respect to said support is limited. 30 105
7. In a seam ironing machine, a work support an ironing block, means for operating said block comprising lever and links connecting the lever and block, and resilient means normally urging said block toward said support, said resilient means being arranged to engage said lever. 35 110
8. In a seam ironing machine, a work support, an ironing block, resilient means normally urging said block toward said support, a stop for limiting the proximal position of the block with respect to the support, a toggle for retracting said block, and a lever connecting said toggle and resilient means, one end of said lever being disposed between said stop and resilient means. 40 115
9. In a seam ironing machine, in combination, a feed roll, a pivotally mounted ironing block, resilient means normally urging said block toward said roll, and means comprising a toggle and a treadle mechanism operatively associated therewith for rendering said resilient means inoperative without materially relieving the strain in said resilient means. 45 120
10. In a seam ironing machine, in combination, a feed roll, a pivotally mounted ironing block, resilient means normally urging said block toward said roll, and means comprising a toggle and a treadle mechanism operatively associated therewith for retracting said block from said roll without a substantial alteration in the strain in said resilient means. 50 125
11. In a seam ironing machine, in combination, a feed roll, a pivotally mounted ironing block, resilient means normally urging said block toward said roll, and means interposed between said block and said resilient means comprising a toggle and a treadle mechanism operatively associated therewith for retracting said block without energizing said resilient means. 55 130
12. In a seam ironing machine, a work-supporting feed roll, an ironing block, a lever, a spring arranged to be compressed by movement of the lever in one direction, means to prevent movement of the lever in the opposite direction, collapsible but normally rigid connections between the lever and the presser block for transmitting pressure from the spring to the presser block, and means for collapsing said normally rigid connections to retract the block. 60 135
13. In a seam ironing machine, a work-supporting feed roll, an ironing block, a lever, a spring arranged to be compressed by movement of the lever in one direction, means for limiting movement of the lever in the opposite direction, collapsible but normally rigid connections between the lever and the presser block constructed and arranged to retract said block without moving said lever, and means for collapsing said normally rigid connections. 65 140
14. In a seam ironing machine, a work-supporting feed roll, a pressure-foot and seam-opening means in juxtaposition thereto, an ironing block, resilient means normally urging said block toward said roll, means comprising a toggle and a treadle mechanism operatively associated therewith for retracting said block without energizing said resilient means, and extensions on the seam-opening means and pressure-foot protruding into the path of movement of the ironing block and the seam-opening means respectively whereby said presser-foot and seam-opening means are retracted with the iron block. 70 145
15. In a seam ironing machine, a work-supporting feed roll, a presser-foot and seam-opening means in juxtaposition thereto, an ironing block, a lever, a spring arranged to be compressed by movement of the lever in one direction, means for limiting movement of the lever in the opposite direction, collapsible but normally rigid connections between the lever and the ironing block for transmitting pressure from the spring to the presser block, means for collapsing said normally rigid connections to retract the block, and extensions on the seam-opening means and presser-foot protruding into the path of movement of the ironing block and the seam-opening means respectively whereby said presser-foot and seam-opening means are retracted with the block. 75 150
16. In a seam ironing machine, a work support, an ironing means, resilient means for causing pressure against said ironing means to urge it toward the support, means for adjustably limiting the movement of the ironing means toward the support, a lever for operating said ironing means arranged normally to abut said last-mentioned means, and links connecting the said lever and ironing means constructed and 80 155

arranged to transmit the yielding pressure of said yielding means from the lever to the ironing means.

17. In a seam ironing machine, a work support, a heated ironing block, seam guiding means, resilient means normally urging said block toward said support, means for successively relieving the pressure between said resilient means and said block and for retracting said block and connections between said block and said guiding means for causing the guiding means to be retracted with the block in order to facilitate the removal of work from the machine.

18. In a seam ironing machine, a work support, an ironing means, resilient means normally urged said ironing means toward said work support, and means for transmitting the pressure of

said resilient means to said ironing means comprising a lever and links connecting said lever and ironing means constructed and arranged to relieve the pressure between the block and the resilient means without removing the stress from the resilient means. 80

19. In a seam ironing machine, a work support, an ironing block, a presser foot, means for urging said block toward said support, and means including a toggle mechanism constructed and arranged to retract the block from the work support without altering the stress in said resilient means, said presser foot having an extension arranged to engage said block as it is retracted whereby said block and presser foot are retracted simultaneously. 85 90
